UNITED STATES PATENT OFFICE

2,373,102

PROCESS FOR BREAKING PETROLEUM
EMULSIONS

Melvin De Groote, University City, and Bernhard Keiser, Webster Groves, Mo., assignors to Petrolite Corporation, Ltd., Wilmington, Del., a corporation of Delaware

No Drawing. Application March 9, 1943,
Serial No. 478,596

6 Claims. (Cl. 252—341)

This invention relates primarily to the resolution of petroleum emulsions.

One object of our invention is to provide a novel process for resolving petroleum emulsions of the water-in-oil type, that are commonly referred to as "cut oil," "roily oil," "emulsified oil," etc., and which comprise fine droplets of naturally-occurring waters or brines dispersed in a more or less permanent state throughout the oil which constitutes the continuous phase of the emulsion.

Another object of our invention is to provide an economical and rapid process for separating emulsions which have been prepared under controlled conditions from mineral oil, such as crude petroleum, and relatively soft waters or weak brines. Controlled emulsification and subsequent demulsification under conditions just mentioned, is of significant value in removing impurities, particularly inorganic salts, from pipeline oil.

The demulsifier or demulsifying agent employed in our process consists of the resultant products obtained by reaction involving polybasic carboxy acids, preferably and conveniently in the form of an ester, such as diethyl phthalate, and acylated ureas, and particularly acylated substituted ureas having in the most preferred form, at least one, and more preferably, at least two hydroxyl radicals.

Such acylated ureas, or substituted ureas, are of the kind in which the acyl radical which is introduced is derived from detergent-forming monocarboxy acids containing eight carbon atoms or more, and not more than 32 carbon atoms, and are characterized by the fact that they combine with alkalis to produce soap or soap-like materials. These detergent-forming acids include fatty acids, resin acids, petroleum acids, etc. For the sake of convenience, these acids will be indicated by the formula R₁COOH. Certain derivatives of detergent-forming acids react with alkali to produce soap or soap-like materials, and are the obvious equivalent of the unchanged or unmodified detergent-forming acids, for instance, instead of fatty acids, one might employ the chlorinated fatty acids. Instead of the resin acids, one might employ the hydrogenated resin acids. Instead of naphthenic acids, one might employ brominated naphthenic acids, etc. Acids obtained by the oxidation of petroleum fractions or waxes may be employed. This type of acid may also be subjected to various modifications, provided such modifications still retain detergent-forming properties.

Reference is made to our co-pending applications Serial Nos. 478,595 and 478,594, filed March 55

9, 1943. Said co-pending applications describe new compositions of matter, for instance, the acylated derivatives of reaction products obtained by combination with diethanolamine and diethyl carbonate. This is illustrated in a very simple aspect by the three following reactions:

The same reaction as above illustrated will take place in connection with other materials, such as dipropanolamine, dibutanolamine, and also in connection with secondary amines of the type ethyl ethanolamine, ethyl propanolamine, ethyl butanolamine, propyl ethanolamine, propyl propanolamine, cyclohexyl ethanolamine, benzyl ethanolamine, phenyl ethanolamine, etc. This is also true in regard to primary amines, such as monoethanolamine, monopropanolamine, monobutanolamine, monopentanolamine, monoheptanolamine, etc.

Reconsidering the three reactions immediately preceding, it is obvious that they may be considered as substituted ureas, substituted urethanes, and carbonic acid esters. The urethanes are, of course, esters of carbamic acid. It is also obvious that the products of reaction above described, the esters, urethanes, the substituted ureas, etc., can be treated with ethylene oxide or some other reagent having a reactive ethylene oxide ring, and subsequently acylated with a high molal monocarboxy acid.

One may introduce a high molal detergent-forming acyl group into a molecule or compound of the kind previously described by the use of suitable reactants, such as ethyl oleate, ethyl naphthenate, ethyl resinate, etc., all of which is described in detail in said aforementioned co-pending applications.

Attention is directed to U. S. patent to De Groote No. 2,083,221, dated June 8, 1937, and No. 2,059,273, dated November 3, 1936, to Piggott. It is to be noted that said aforementioned De Groote patent gives a more elaborate description of the monocarboxy detergent-forming acids herein contemplated as reactants. It is also believed, in the

light of subsequent investigations, that in many instances reaction with a compound having a reactive ethylene oxide ring, such as ethylene oxide, propylene oxide, butylene oxide, glycid, or the like, may result in the complete elimination of any amino hydrogen atom; as shown in both of said aforementioned patents, i. e., the De Groote and Piggott patents.

It is also obvious that substituted ureas in considerable variety and suitable for use as a reactant in preparing compounds of the kind herein contemplated, both for use as demulsifiers and for other uses, are readily obtainable from a variety of amines.

It may be well to point out that our preferred detergent-forming acid, as a source of the required acyl radical, is exemplified by the higher fatty acids, for instance, oleic, ricinoleic, linoleic, linolenic, stearic, lauric, etc. One need not employ a single higher fatty acid, but may employ 15 the fatty acids, particularly in ester form, as derived from various natural sources. In other words, one may employ the fatty acids or esters of fatty acids as they occur in mixed form in cottonseed oil, corn oil, castor oil, soyabean oil, olive oil, cocoanut oil, teaseed oil, linseed oil, etc.

In many instances, one need not separate the acylated ureas, or substituted ureas, of the kind herein described from other members of a co-generic mixture, such as esters of carbonic acids, or urethanes. Previous reference in regard to this aspect has already been made in connection with our two co-pending applications Serial Nos. 478,594 and 478,595, filed March 9, 1943. The use of such cogeneric mixtures as reactants will serve to yield a final product which contains a significant amount of the compositions or new compounds herein contemplated.

Attention is further directed to the fact that in various examples, particularly those herein-after described in detail, there is an intermediate step of oxyethylation prior to treatment with ethyl oleate or the like and diethyl phthalate or the like. It is to be noted that in some instances it is more advantageous to reverse the procedure and react with a compound such as diethyl phthalate first, and then follow with an acylation reaction of the kind in which there is introduced a high molal detergent-forming monocarboxy radical or acylated radical.

It is also of interest to note that, as previously pointed out, the acylation reactions herein contemplated, whether involving the introduction of an acyl radical from a high molal detergent-forming monocarboxy acid, or the acyl radical of a polybasic carboxy acid, need not be limited to the esterification type of acylation, i. e., reaction involving an alcoholic hydroxyl radical, but includes reactions involving an amino hydrogen atom, i. e., amidification. In other words, in some of the subsequently described examples, it is obvious that if oxyethylation were omitted, the product would still be susceptible to reactions of the kind described, i. e., acylation reactions.

It would appear that perhaps the simplest and most attractive reaction for the formation of compounds of the kind herein contemplated, or rather, for the formation of certain desirable intermediates, would be a reaction involving the amide of a high molal detergent-forming acid, such as oleamide, ricinoleamide, etc., with diethyl carbonate, or the like, in the ratio of two moles of the amide for each mole of diethyl carbonate, particularly in the presence of a small amount of catalyst, such as sodium bicarbonate. 75

Our experience with this reaction has been that the yields have been insignificantly low or nil, although possibly, under different conditions, improved results could be obtained. For this reason, our preference is to follow the procedure illustrated by the following examples:

SUBSTITUTED UREA

Example 1

10 Diamylurea is prepared from amyloxamine, and a cyanate. (See Berichte 12, 1331, Custer.) Other equally suitable methods may be employed.

SUBSTITUTED UREA

Example 2

The same procedure is followed as in the preceding example, except that cyclohexylamine is substituted for amyloxamine.

SUBSTITUTED UREA

Example 3

The same procedure is followed as in Example 1, preceding, except that benzylamine is substituted for amyloxamine.

SUBSTITUTED UREA

Example 4

The same procedure is followed as in Example 1 preceding, except that aniline is substituted for amyloxamine.

AMIDO-TYPE ACYLATED SUBSTITUTED UREAS

Example 1

35 Symmetrical diamyl urea is reacted with a low molal ester of a hydroxylated high molal detergent-forming acid, such as the ethyl ester of ricinoleic acid, the ethyl ester of hydroxystearic acid, the ethyl ester of dihydroxystearic acid, the 40 ethyl ester of hydroxylated acids obtained by the oxidation of petroleum wax, etc. Equal molal ratios are employed. One amino hydrogen atom remains without entering into reaction.

AMIDO-TYPE ACYLATED SUBSTITUTED UREAS

Example 2

The same procedure is followed as in the preceding example, except that instead of employing the amyloxylated urea, one employs instead, various substituted ureas described under the heading "Substituted ureas, Examples 2-4."

OXYALKYLATED SUBSTITUTED UREAS

Example 1

55 1 pound mole of urea is treated with at least four pound moles of ethylene oxide (see aforementioned U. S. patent to De Groote No. 2,083,221, and U. S. patent to Piggott No. 2,059,273).

OXYALKYLATED SUBSTITUTED UREAS

Example 2

One pound mole of amyloxylated urea of the kind described under the heading "Substituted ureas, Example 1," preceding, is treated with two pound moles of ethylene oxide so as to yield the corresponding oxyalkylated derivative.

OXYALKYLATED SUBSTITUTED UREAS

Example 3

Instead of employing amyloxylated urea as a reactant, one employs instead various other substituted ureas of the kind described under the previous headings "Substituted ureas, Examples 2-4," inclusive.

OXYALKYLATED SUBSTITUTED UREA

Example 4

The same procedure is followed as in the three preceding examples, except that some other reactant containing a reactive ethylene oxide ring, for instance, propylene oxide, butylene oxide, glycid, or the like, are employed instead of ethylene oxide.

ESTER-TYPE ACYLATED SUBSTITUTED UREAS

Example 1

Hydroxylated substituted ureas, preferably having at least two alcoholic functions, are reacted with low molal esters of high molal detergent-forming acids which may or may not be hydroxylated, for example, one pound mole of an oxyalkylated urea exemplified by Oxyalkylated Example 1, preceding, is reacted with one pound mole of ethyloleate.

ESTER-TYPE ACYLATED SUBSTITUTED UREAS

Example 2

Instead of using an oxyalkylated urea of the kind exemplified by Example 2, preceding, one employs the type exemplified by Examples 3 or 4, preceding.

ESTER-TYPE ACYLATED SUBSTITUTED UREAS

Example 3

Ethylicinoleate, or some other low molal ester, such as the methyl or propyl ester, is substituted for ethyloleate in the preceding example.

ESTER-TYPE ACYLATED SUBSTITUTED UREAS

Example 4

Ethyl naphthenate is substituted for ethyloleate in Examples 1 or 2, preceding.

ESTER-TYPE ACYLATED SUBSTITUTED UREAS

Example 5

Ethyl resinate, prepared by the esterification of rosin with ethyl alcohol, is substituted for ethyloleate in Examples 1 and 2, preceding.

FINAL COMPOSITION OF MATTER

Example 1

1 pound mole of an amido acylated substituted urea, as exemplified by the type of material described under Example 1, preceding, is reacted with 1 pound mole of diethyl phthalate. The substituted urea is preferably reacted with 2 to 4 moles of an oxyalkylating agent, prior to reaction, with diethyl phthalate. Ethylene oxide is especially suitable.

FINAL COMPOSITION OF MATTER

Example 2

The same procedure is followed as in Ester type acylated substituted ureas, Example 1, preceding, but there is employed as a reactant the type of material described under the heading "Amido-type acylated substituted ureas, Example 2."

FINAL COMPOSITION OF MATTER

Example 3

The same procedure is followed as in Examples 1 and 2, preceding, but instead of the previous reactants employed in conjunction with diethyl phthalate, there is employed instead a material of the kind described under the heading "Ester-type acylated substituted ureas, Example 1."

FINAL COMPOSITION OF MATTER

Example 4

The same procedure is followed as in the preceding example, except that the reactant employed in conjunction with diethyl phthalate is a material of the kind typified by "Ester-type acylated substituted ureas, Examples 2 to 5", inclusive.

FINAL COMPOSITION OF MATTER

Example 5

The same procedure is followed as in the preceding examples, except that where the reactant employed in conjunction with diethyl phthalate is polyfunctional, the molar proportion of diethyl phthalate to the acylated intermediate ("acyl" having reference to the high molal detergent-forming monocarboxy acid radical) is increased to a polymolecular proportion, for instance, 2 to 1 or 3 to 1.

FINAL COMPOSITION OF MATTER

Example 6

The same procedure is followed as in the preceding Examples 1 to 5, inclusive, except that the diethyl ester of some other suitable polybasic carboxy acid, such as diethyl maleate, diethyl fumarate, diethyl adipate, diethyl succinate, diethyl azaleate, diethyl citrate, diethyl citronate, diethyl sebacate, diethyl tartrate, or the like, is employed.

FINAL COMPOSITION OF MATTER

Example 7

The same procedure is followed as in Examples 1 to 6, preceding, except that some other low molal alkyl ester, particularly a dialkyl ester, is employed instead of the diethyl ester. For instance, one might employ dimethyl phthalate, ethyl methyl phthalate, dipropyl phthalate, methyl propyl phthalate, ethyl propyl phthalate, dibutyl phthalate, propyl butyl phthalate, ethyl butyl phthalate, etc. In various of the above instances, the acid itself or anhydride, such as phthalic anhydride, maleic anhydride, citraconic anhydride, or the acid, such as adipic acid, azelic acid, or the like, may be used.

Reference is again made to the fact that it has been previously noted that in some instances it is more convenient and desirable to react a selected raw material or intermediate with a reactant such as diethyl phthalate, or the like, and subsequently react with ethyl oleate, ethyl ricinoleate, or the like.

In the preceding examples, it is to be noted that the reactions, in part, involve conventional acylation, which generally means the elimination of water, or an alcohol, or possibly, ammonia. In view of the employment of a reactant such as

ethyl oleate, or ethyl ricinoleate, it is obvious that acylation will take place with the elimination of ethyl alcohol. Naturally, methyl oleate, methyl ricinoleate, propyl oleate, propyl ricinoleate, butyl oleate, butyl ricinoleate, or the like, might be employed. Such reactions are generally conducted at a point somewhat in excess of the boiling point of the alcohol involved. For instance, where the reaction involves the evolution of ethyl alcohol, a suitable working temperature is approximately 150° C. On the other hand, if butyl oleate, or butyl ricinoleate is employed, a suitable temperature would be approximately 200° C. Such reactions are conducted with constant stirring, and generally take place

75 in a comparatively short period of time, for in-

stance, 2-12 hours. Completeness of reaction is generally indicated by the fact that substantially the theoretical amount of alcohol, after making allowance for impurities and mechanical loss, is evolved and may be condensed and measured. The same applies when the acylation reaction involves a reactant such as diethyl phthalate, or the like. This is also true in regard to reactions involving diethyl carbonate. The diethyl carbonate reactions are sometimes catalyzed by the addition of a small amount, for instance, approximately $\frac{1}{4}$ % to $\frac{1}{2}$ % of sodium bicarbonate.

Conventional acylation reactions of the kind involved in the formation of oleoamide, or ricinoleoamide, are so well known that description is not required.

We have found that the most suitable products for various purposes, and particularly, for demulsification, are sub-resinous, semi-resinous, or balsam-like products, and are preferably derived from polyfunctional acylated reactants, in which the acyl group is derived from a high molal detergent-forming monocarboxy acid. We have found that such products are soluble to a fairly definite state, for example, 5% in some solvent, such as water, alcohol, benzene, dichloroethyl ether, acetone, cresylic acid, dilute acidic acid, dioxane, or the like. This is simply another way of stating that it is preferable, that the product be one of the sub-resins, which are commonly referred to as an A resin, or a B resin, as distinguished from a C resin, which is a highly infusible, insoluble resin. (See Ellis, Chemistry of Synthetic Resins, 1935, page 862, et seq.)

It is our preference that the products be obtained from polyhydroxylated acylated products by reaction with diethyl phthalate, or the like. Indeed, it is our preference to employ polyhydroxylated acylated products of the kind in which there is no amino hydrogen atom present, i. e., the kind in which acylation is limited entirely to the esterification type of reaction.

In view of what has been said as to the numerous and varied aspects of the present invention, it is apparent that a monohydroxylated acylated product free from an amino hydrogen atom, can form only a monomer such as a complete ester or fractional ester. Thus, if the hydroxylated acylated products employed as reactants for combination with diethyl phthalate, or the like, they may be considered as an alcohol, i. e., a monohydric or polyhydric alcohol. If an alcohol is indicated by the formula $Y'(OH)_n$, where n indicates the number 1 or more, and if a polybasic acid body be indicated by the formula

where n indicates the number 2 or more, then the reaction between a monohydric alcohol and a polybasic acid will result in a compound which may be indicated by the following formula: $YX(COOH)_n'$, wherein n' indicates the number 1 or more, and which is in reality a contraction of a more elaborate structural formula, in which X' and Y' are joined by a carboxyl radical or residue. Assuming, however, as would be true in the majority of cases, that the alcohol actually would be a polyhydric alcohol, and that the acid body would be polybasic in nature, for instance, if one employed a diphthalate of a polyhydroxylated ester diamide of the kind previously described, then examination reveals that the formula might result in a combination, in which there were neither residual carboxyl radicals, nor residual

hydroxyl radicals, or might result in compounds in which there were residual hydroxyl radicals, and no residual carboxyl radicals, or compounds where there might be residual carboxyl radicals and no residual hydroxyl radicals; or there might be both. This is indicated by the following:

in which q indicates a small whole number (one in the case of a monomer, and probably not over 10, and usually less than 5, and m' and n' indicate the number 1 or more, and m'' and n'' indicate zero or a small or moderately sized whole number, such as zero, one or more, but in any event, probably a number not in excess of 4-8.

Actually, in view of what has been said as to the most desirable procedure of manufacture, in order to avoid decomposition, it is obvious that the free carboxyl atom above will not appear, but the ester radical, i. e., one where the carboxylic hydrogen atom has been replaced by a methyl, ethyl, propyl, or butyl group, will appear.

It is also obvious that the solubility of the reagents herein described may be enhanced by oxyalkylation, i. e., the final composition of matter—exemplified by Examples 1 to 7, preceding, may, in various instances, be subjected to treatment with a reagent containing a reactive ethylene oxide ring, for example, ethylene oxide, propylene oxide, butylene oxide, glycid, etc. In such instances, the ethylene oxide or equivalent reactant reacts with any amino hydrogen atom present or any hydroxyl radical present, or may cause a rearrangement or re-esterification by replacing a low mole alkyl radical, such as an ethyl radical, by a hydroxy ethyl radical, or an equivalent radical, in which the carbon atom chain is interrupted one or more times by an oxygen atom. Compare reactions involved when a glyceride such as a castor oil or olive oil is treated with ethylene oxide.

Conventional demulsifying agents employed in the treatment of oil field emulsions are used as such, or after dilution with any suitable solvent, such as water; petroleum hydrocarbons, such as gasoline, kerosene, stove oil; a coal tar product, such as benzene, toluene, xylene, tar acid oil, cresol anthracene oil, etc. Alcohols, particularly aliphatic alcohols, such as methyl alcohol, ethyl alcohol, denatured alcohol, propyl alcohol, butyl alcohol, hexyl alcohol, octyl alcohol, etc., may be employed as diluents. Miscellaneous solvents, such as pine oil, carbon tetrachloride, sulfur dioxide extract obtained in the refining of petroleum, etc., may be employed as diluents. Similarly, the material or materials employed as the demulsifying agent of our process may be admixed with one or more of the solvents customarily used in connection with conventional demulsifying agents. Moreover, said material or materials may be used alone, or in admixture with other suitable well known classes of demulsifying agents.

It is well known that conventional demulsifying agents may be used in a water-soluble form, or in an oil-soluble form, or in a form exhibiting both oil and water solubility. Sometimes they may be used in a form which exhibits relatively limited oil solubility. However, since such reagents are sometimes used in a ratio of 1 to 10,000, or 1 to 20,000, or even 1 to 30,000, such an apparent insolubility in oil and water is not sig-

nificant, because said reagents undoubtedly have solubility within the concentration employed. This same fact is true in regard to the material or materials employed as the demulsifying agent of our process.

We desire to point out that the superiority of the reagent or demulsifying agent contemplated in our process is based upon its ability to treat certain emulsions more advantageously and at a somewhat lower cost than is possible with other available demulsifiers, or conventional mixtures thereof. It is believed that the particular demulsifying agent or treating agent herein described will find comparatively limited application, so far as the majority of oil field emulsions are concerned, but we have found that such a demulsifying agent has commercial value, as it will economically break or resolve oil field emulsions in a number of cases which cannot be treated as easily or at so low a cost with the demulsifying agents heretofore available.

In practising our process for resolving petroleum emulsions of the water-in-oil type, a treating agent or demulsifying agent of the kind above described is brought into contact with or caused to act upon the emulsion to be treated, in any of the various ways, or by any of the various apparatus now generally used to resolve or break petroleum emulsions with a chemical reagent, the above procedure being used either alone, or in combination with other demulsifying procedure, such as the electrical dehydration process.

The demulsifier herein contemplated may be employed in connection with what is commonly known as down-the-hole procedure, i. e., bringing the demulsifier in contact with the fluids of the well at the bottom of the well, or at some point prior to the emergence of said well fluids. This particular type of application is decidedly feasible when the demulsifier is used in connection with acidification of calcareous oil-bearing strata, especially if suspended in or dissolved in the acid employed for acidification.

The words "acidyl" and "acyl" and the words "acydylation" and "acylation" are usually used synonymously. Compounds of the type herein contemplated, and particularly for use as demulsifiers, are characterized by having two different types of carboxylic acid radicals, or carboxylic acyl radicals present. One type is derived from high molal detergent-forming monocarboxy acids, such as higher fatty acids, and the other type is derived from polybasic acids, particularly phthalic acid, and the like, or other suitable derivatives thereof, such as diethyl phthalate. For purpose of clarity, in the hereto attached claims, the use of the words "acyl," "acylated" and "acylation" is limited to high molal monocarboxy detergent-forming acids, whereas, the expressions "acidyl," "acidylated" and "acydylation" are used in connection with polybasic carboxy acids.

Attention has been previously directed to the fact that the expression "alkanol" includes the type of hydroxy aliphatic radicals in which the carbon atom chain is interrupted at least once by an oxygen atom, i. e., contains an ether linkage. We have found the type in which the ether linkage recurs a fairly large number of times, for instance, 4 to 18 times, represents the most desirable type of demulsifier, and also the most desirable type of compound for other purposes enumerated. Unquestionably, the recurring ether linkage, particularly that derived from low

molal oxyalkylated agents, such as ethylene oxide, propylene oxide, butylene oxide and glycidyl, has a distinctly functional significance.

Having thus described our invention, what we claim as new and desire to secure by Letters Patent is:

1. A process for breaking petroleum emulsions of the water-in-oil type, which consists in subjecting the emulsion to the action of a demulsifier, comprising a sub-resinous acidylated derivative of an acylated substituted urea containing at least one nitrogen-linked alkanol radical; the acyl radical being that of a detergent-forming monocarboxy acid having at least 8 and not more than 32 carbon atoms; said acidyl radical being a polybasic carboxy acid radical.
2. A process for breaking petroleum emulsions of the water-in-oil type, which consists in subjecting the emulsion to the action of a demulsifier, comprising a sub-resinous acidylated derivative of an acylated substituted urea containing at least one nitrogen-linked alkanol radical having at least 4 and not more than 18 ether linked oxygen atoms; the acyl radical being that of a detergent-forming monocarboxy acid having at least 8 and not more than 32 carbon atoms; said acidyl radical being a polybasic carboxy acid radical.
3. A process for breaking petroleum emulsions of the water-in-oil type, which consists in subjecting the emulsion to the action of a demulsifier, comprising a sub-resinous acidylated derivative of an acylated substituted urea containing at least one nitrogen-linked alkanol radical having at least 4 and not more than 18 ether linked oxygen atoms; the acyl radical being that of a detergent-forming monocarboxy acid having at least 8 and not more than 32 carbon atoms; said acidyl radical being a dibasic carboxy acid radical.
4. A process for breaking petroleum emulsions of the water-in-oil type, which consists in subjecting the emulsion to the action of a demulsifier, comprising a sub-resinous acidylated derivative of an acylated substituted urea containing at least one nitrogen-linked alkanol radical having at least 4 and not more than 18 ether linked oxygen atoms; the acyl radical being that of a higher fatty acid having at least 8 and not more than 32 carbon atoms; said acidyl radical being a dibasic carboxy acid radical.
5. A process for breaking petroleum emulsions of the water-in-oil type, which consists in subjecting the emulsion to the action of a demulsifier, comprising a sub-resinous acidylated derivative of an acylated substituted urea containing at least one nitrogen-linked alkanol radical having at least 4 and not more than 18 ether linked oxygen atoms; the acyl radical being that of a higher fatty acid having 18 carbon atoms; said acidyl radical being a dibasic carboxy acid radical.
6. A process for breaking petroleum emulsions of the water-in-oil type, which consists in subjecting the emulsion to the action of a demulsifier, comprising a sub-resinous acidylated derivative of an acylated substituted urea containing at least one nitrogen-linked alkanol radical having at least 4 and not more than 18 ether linked oxygen atoms; the acyl radical being that of a higher unsaturated fatty acid having 18 carbon atoms; said acidyl radical being a dibasic carboxy acid radical.

MELVIN DE GROOTE,
BERNHARD KEISER.
